LID SEAMING MACHINE

Frank Oscar Levi Chorlton and Herbert Mayson,
Bury, England; said Mayson assignor to said
Chorlton

Application June 7, 1937, Serial No. 146,952
In Great Britain February 20, 1936

10 Claims. (CL. 113—82)

This invention is for improvements in or relating to machines, for seaming lids on cans or like containers, of the type comprising a sealing chamber within which the seaming operation takes place in vacuo or in an inert gas, said sealing chamber being provided with a door which is opened for the introduction of the can and is closed during the seaming operation, a fluid control valve adapted during a seaming operation to connect the sealing chamber to a source of sub-atmospheric pressure or inert gas, means for positioning and supporting the containers for rotation relatively to a seaming means, and a container rotating mechanism connected or adapted to be connected to a source of motive power, the seaming operation being effected by the rotation of the can with the lid in position thereon, about the axis of the can, and in engagement with a seaming means.

20 An object of the present invention is to provide an efficient and inexpensive machine of the type above referred to, which, with the exception of the power-operated means for rotating the can and maintaining the sub-atmospheric air pressure or the pressure of the inert gas, is hand-operated.

Another object is to provide a machine of the type above referred to according to which the actuated parts of each of the several means for closing the sealing chamber door, for operating the fluid control valve, and for positioning the containers for rotation relatively to the seaming means are arranged in proximity to a single manually operable lever and are all actuated thereby, the sequence of the several operations being automatically determined by interlocking means.

Other objects and features of the invention will be pointed out in the following specific description.

The invention will be further described with reference to the accompanying drawings which show one example of a seaming machine for seaming a lid onto a can in vacuo, and incorporating an operating and control mechanism according to the present invention. In the drawings:—

45 Figure 1 is a side elevation partly in section of the complete machine.

Figure 2 is a fragmentary sectional elevation, to an enlarged scale, of a clutch mechanism through which rotation of the can at the appropriate time is effected.

50 Figure 3 is a fragmentary elevation of the hand operating mechanism by which the various operations are effected in sequence.

55 Figure 4 is a fragmentary front elevation on the line IV—IV of Figure 1, but with the hand

lever pulled down to the position of closing the sealing chamber door and just prior to lateral movement to operate the suction valve,

Figure 5 is a fragmentary view showing the sequence of positions of the operating mechanism when it is moved from the position shown in Figure 1 to effect a seaming operation on the can. 5

Figures 6 and 7 are respectively front and side elevations of the machine, and 10

Figure 8 is a fragmentary view of a modification.

Referring to the drawings (Figures 1-7) the machine comprises a base frame 10 on which is mounted a hollow column 11 supporting a sealing chamber 12 adapted to be closed by a sliding door 13. During a seaming operation the can and lid are supported in the chamber 12 between an axially movable table or chuck 14 and a freely rotatable axially fixed chuck 15, and the seaming operation is effected by means of one or more seaming rollers 16. The rollers 16 are mounted on an arm 16^a on a shaft 16^b and are moved against the action of a spring 16^c. The chucks 14 and 15 are journaled in gas-tight bearings 20 and the chuck 14 is rotated to effect rotation of a can during the seaming operation from a motor 17 through a friction clutch comprising a constantly rotating element 19 and an axially movable element 20, a V-pulley 19^a on the element 30 19 being driven from a V-pulley 17^a on the motor 17 through a rope or V-belt 21 passing over jockey guide pulleys 23 and 24, adjustable by means of any suitable form of screw device 25 to vary the tension of the belt. The motor 17 also 35 drives a suction pump 26 connected by a conduit 27 to the hollow column 11 which constitutes a suction reservoir, and the sealing chamber 12 is put in communication with the suction reservoir as hereinafter described by means of an axially slidible piston valve 28 (see Figure 4) controlling the passageways 29, 30, and the port 28^b 40 opening to atmosphere, the end of the passageway 30 communicating with the interior of the column 11 through a chest 31 mounted on the upper part of said column. The port 28^b is closed by the part 28^a of the valve 28 when the latter moves to put the chamber into communication with the exhausting means. 45

After a can fitted with a lid which is to be 50 seamed to the can has been placed on the chuck 14, the door 13 is closed and the chuck 14 is raised so as to bring the upper part of the can with the lid in position thereon into proximity with the chuck 15, after which the valve 28 is 55

operated to connect the chamber 12 to the vacuum reservoir and the clutch element 20 is brought into engagement with the clutch element 19 to effect rotation of the chuck 14 and thereby 5 of the can which is now firmly gripped between the chucks 14 and 15. The lid is generally dished to receive the chuck 15 by which it is centered on the can.

10 This sequence of operations is effected from a single hand control mechanism comprising a hand-operated main lever 32. The hand-operated lever 32 is mounted on a rock shaft 33 carried in fixed bearings 35 supported by brackets 36; the bore of the lever is substantially greater
15 than the diameter of the shaft and the lever is connected to the shaft by a transverse pivot pin 34; the lever therefore is capable of movement (which will be termed the primary movement) in a plane at right angles to the axis of the shaft
20 33, and thereby impart angular movement to the shaft, or to have secondary movement in a plane at right angles to the pivot 34 without imparting angular movement to the shaft 33. A lever 31 is loosely mounted on the shaft and is connected
25 to the door 13 by the links 15.

30 to the door 15 by the lever 38. There is keyed to the shaft 33 a lever 38 which is connected by a connecting rod 39 to a bell-crank lever 40, 40'. The chuck 14 is moved to position the container and is connected to the driving element 19 of the clutch by the movement of the arm 40' of the lever 40, 40', the arrangement being as follows:—The clutch member 20 has a sleeve 47 which is mounted in a bearing 47^a so as to be capable of rotation and axial movement therein, the clutch member 19 is rotatably mounted in the fixed bearing 19^a by which it is held against axial movement; the bearing 19^a has a hollow bore through which passes a spindle 45, the upper end of which is connected to the chuck 14, said spindle being axially movable relatively to the sleeve but being feathered or splined thereon so as to be rotated by the sleeve and clutch member 20.

45 The sleeve 47 is extended so as to form a coupling 46 and a head 45^a of the spindle engages a shoulder 46^b of the coupling; the interior of the coupling is screw-threaded so as to take a hollow screw-threaded nut 48 having an internally projecting flange, and a spring 49 is interposed 50 between the said flange and the face of the head 45^a of the spindle 45. Axial movement is imparted to the coupling 46 by the arm 40' of the bellcrank lever through a spring connecting rod comprising two portions 41, 42 mounted in a casing 44 in which they are movable axially but 55 maintained in axial alignment, and are pressed apart by a spring 43, the part 41 is pivotally connected to the arm 40', and the upper end 42 is pivotally connected to a part 46^a housed in the coupling 46 which latter is capable of rotation 60 but not of axial movement relatively to the part 41.

41. The rocking lever 37 which is loosely jour-
65 nalled on the rock shaft 33 is coupled to the door
13 through links 56 and is operatively connected
to the hand lever 32 through a gate device 51
formed on the lever 37 and having an aperture
70 through which the hand lever 32 projects, the
aperture comprising a slot 52 and a lateral recess
53 which provides an abutment 54 for the lever
as shown in Figure 4. The engagement of the
door with the bottom of the door aperture will
75 limit the downward movement of the lever 37 and
the gate but if desired a pin or the like fixed on

the frame of the machine may be provided to limit movement of the gate.

The hand lever 32 is restrained in the lateral recess 53 by an arm 32^a, see Fig. 6, until the hand lever 32 has moved to the position in which the door is closed (that is to say, the position shown in Figure 4), when the hand lever 32 reaches this position it is free of the restraining means 32^a and can move clear of the abutment 54 to undergo its secondary movement for operating the valve controlling the exhausting of the sealing chamber. The passageway 29, 30 in the wall of the sealing chamber which connects the interior of the sealing chamber with the reservoir 31 is arranged so that the two parts 29 and 30 are laterally displaced on opposite sides of a cylindrical bore which intersects the passageway, and in which slides a piston valve 28, 28^a. The bore has a port 28^b leading to the atmosphere.

When the valve is in its extreme right position, 20 that shown in Figure 4, the interior of the sealing chamber communicates through the upper part 29 of the passageway, the bore and the port 28^b with the atmosphere, the part of the passageway 30 leading to the reservoir 31 being 25 closed by the part 28 of the valve; when the valve is moved to its extreme left position, the reservoir 31 communicates with the interior of the sealing chamber 12 through the passageway 29, 30, the part 28^a of the valve closing the port 28^b before the passageway is opened. 30

26 before the passageway 29, 30. The piston valve 28 is adapted to be slid axially in a valve chamber 55 to put the parts of the passageway 29, 30, into and out of communication with each other, by means of a lever 56 35 pivoted at 57 on the frame of the machine and its tail 56^a is connected to the piston valve through the pivot pin 58. The upper part of the lever 56 bears against one side of the hand lever 32 as shown in Figure 4, so that when said hand lever is moved angularly about its pin 34 and laterally with respect to the rock shaft 33 to bring the hand lever out of engagement with the abutment 54 of the gate, the lever 56 is rocked about its pivot to move the piston valve 28 to put the ports 29 and 30 into communication with each other. The return movement of the piston valve may if necessary be effected by springs.

The operation of the machine above described is as follows:—

A can which may initially be located on the table 59 is placed on the chuck 14 and the hand lever 32 is pulled down from the position shown in Figure 1 to that shown in full lines in Figure 5. This movement of the hand lever through the engagement thereof with the abutment 54 of the gate, moves the lever 37 into the position shown in full lines in Figure 5, and thereby closes the door 13. At the same time the lever 38 is moved by the rock shaft so as to effect an initial elevation of the chuck 14 so as to bring the can with the lid in position thereon into close proximity with the chuck 15. This movement of the lever 38 is not sufficient to bring the clutch element 20 into engagement with the driven element 19 and the hand lever 32 is now moved laterally out of engagement with the abutment 54 of the gate, thereby operating the lever 56 and valve 28 to exhaust the chamber 12; after which the hand lever can be given a further downward movement in the slot 52 so as to bring the clutch element 20 into engagement with the clutch element 19 to transmit a drive to the chuck 14 between which and the chuck 15, the can is firmly held and rotated. The seaming rollers 16 of which there

- may be two, are then brought successively into engagement with the upper edge of the can and the edge of the lid by means of a hand lever 60 to form the seam, after which the hand lever 32 5 can be released and will return to the position shown in Figure 1 under the action of a weight 61, thus lowering the chuck 14, disengaging the clutch 18, closing the valve 28 and finally opening the door 13.
- 10 It will be appreciated from the above description that the present invention provides a very simple operating mechanism for effecting a vacuum seaming operation on a can, the various operations being effected by only two manually 15 operated members, namely, the lever 32 and the lever 60 and furthermore the operations effected through the lever 32 take place in the correct sequence and independently of the operator.

In the modification shown in Figure 6 the upper 20 per chuck is rotated from the motor 17 in a similar manner to the lower chuck in the arrangement shown in Figure 1. The spindle 15^a of the upper chuck has splined on it one element 20^a of a clutch, the other element 19^a of which is 25 freely journalled on the spindle 15^a and is driven from the motor 17 by means of the belt 21. Movement of the clutch element 20^a into and out of engagement with the element 19^a is effected by the hand lever 32 through a lever 62 30 fixed on the rocking shaft 33, a link 63 and a bell-crank-lever 64 pivoted on a bracket mounted on the sealing chamber 12. The lower chuck is rotatably supported and is adjustable axially to 35 position a can and hold it in driving engagement with the upper chuck 15 in a manner similar to that shown in Figure 1.

What is claimed is:—

1. In a machine of the type specified, the combination with a sealing chamber having an opening through which the containers are introduced and having a passageway through its wall; a door closing the said opening; a valve closing the said passageway; seaming means within the chamber; means for positioning the containers in relation to the seaming means; and means for rotating the positioned container; of a main operating part connected to the door, the positioning means and the valve, and being movable by hand in a primary direction, and also movable 40 by hand in a secondary direction, said primary movement closing the door and operating the positioning means, and said secondary movement opening the valve.

2. In a machine of the type specified, the combination with a sealing chamber having an opening through which the containers are introduced and having a passageway through its wall; a door closing the said opening; a lever for actuating the door; a valve closing the said passageway; seaming means within the chamber; means for positioning the containers in relation to the seaming means; and means for rotating the positioned container; of a main operating lever connected to the door actuating lever, the positioning means and the valve, and being movable by hand in a primary direction and also movable by hand in a secondary direction, said primary movement operating the door actuating lever and the positioning means, and said secondary movement opening the valve; and a gate-lock device interposed between the door actuating lever and the main operating lever, said gate-lock having a transversely disposed locking part which, when the operating lever has, by primary movement, been moved from its initial position until it has

closed the door, prevents the further primary movement being imparted to the operated lever until the secondary movement to open the valve has been imparted thereto.

3. In a machine of the type specified, the combination with a sealing chamber having an opening through which the containers are introduced and having a passageway through its wall; a door closing the said opening; a lever for actuating the door; a valve closing the said passageway; seaming means within the chamber; an axially movable chuck for positioning the containers in relation to the sealing means; a clutch having a power-operated driving member and a driven member connected to the chuck, and an axially movable chuck and clutch actuating member to impart axial movement to the chuck to position it, and axial movement to the driven clutch member to cause engagement of the clutch; of a main operating lever connected to the door actuating lever, the chuck and clutch actuating member and the valve, and being movable by hand in a primary direction and also movable by hand in a secondary direction, said primary movement closing the door and operating the chuck and clutch actuating member, and the secondary movement opening the valve; and a gate-lock device interposed between the door actuating lever and the main operating lever, said gate-lock having a transversely disposed locking part which, when the operating lever has, by primary movement, been moved from its initial position until it has closed the door, prevents the further primary movement being imparted to the operating lever until the secondary movement to open the valve has been imparted thereto.

4. The combination with the elements in claim 3, a sleeve connected to an axially movable driven part of the clutch; said sleeve having an extension forming a coupling unit to which axial movement is imparted by the main operating handle; a spindle splined in the sleeve, one end being connected to the chuck and the other end having a head one face of which engages a shoulder of the sleeve; and a spring interposed between the other face of the head of the spindle and a second shoulder in the coupling unit.

5. The combination with the elements claimed in claim 2, of a fixed locking piece adapted to engage the main operating lever and to prevent secondary movement being imparted to it while it is being moved in a primary direction from its initial position to a position in which it has closed the door.

6. The combination with the elements claimed in claim 3, of a fixed locking piece adapted to engage the main operating lever and to prevent secondary movement being imparted to it while it is being moved in a primary direction from its initial position to a position in which it has closed the door.

7. Apparatus as claimed in claim 2, in which the sealing chamber is provided with a cylindrical bore intersecting the passageway through its wall, in which the said passageway is divided by the bore into two laterally displaced portions on opposite sides of the bore, and in which a port opening into the bore is connected to the atmosphere; and in which the valve is a piston valve reciprocated axially by the main operating lever and fitting the said cylindrical bore, adapted in the one extreme position to close the part of the passageway remote from the sealing chamber and to connect the part of the passageway opening into the sealing chamber to the said

port, and in its other extreme position to close the said port and to open both parts of the passageway.

8. Apparatus as claimed in claim 3, in which the sealing chamber is provided with a cylindrical bore intersecting the passageway through its wall, in which the said passageway is divided by the bore into two laterally displaced portions on opposite sides of the bore, and in which a port opening into the bore is connected to the atmosphere; and in which the valve is a piston valve reciprocated axially by the main operating lever and fitting the said cylindrical bore, adapted in the one extreme position to close the part of the passageway remote from the sealing chamber and to connect the part of the passageway opening into the sealing chamber to the said port, and in its other extreme position to close the said port and to open both parts of the passageway.

9. In a machine of the type specified, the combination with a sealing chamber having an opening through which the container is introduced, and having a passageway through its wall; a door closing the said opening; a valve closing the

said passageway; seaming means within the chamber; means for positioning the containers in relation to the seaming means; and means for rotating the positioned container; of a main operating shaft; a main operating lever pivotally connected to the said shaft by a transverse pivot; a lever keyed to the shaft and connected to the said positioning means; a lever connected to the door and loosely mounted on the said shaft; a gate-lock device connecting the loosely mounted lever to the main operating lever; and a lever in proximity to the main lever which is actuated to close the valve by secondary movement of the main operating lever about the transverse pivot thereof.

10. Apparatus as claimed in claim 3, in which the connection between the operating lever and the coupling extension of the clutch sleeve is made through a bellcrank lever, one arm of which is actuated by the operating lever, and the other arm of which is connected by a resilient connecting rod to the coupling extension.
